CLAIM

The ornamental design for a bib for a fuel tank inlet conduit, as shown and described.

DESCRIPTION

FIG. 1 is a front and left side perspective view of a bib for a fuel tank inlet conduit embodying our new design;

FIG. 2 is a front elevation view thereof;

FIG. 3 is a rear elevation view thereof;

FIG. 4 is a left side perspective view thereof;

FIG. 5 is a right side elevation view thereof;

FIG. 6 is a top plan view thereof;

FIG. 7 is a bottom plan view thereof; and,

FIG. 8 is a front perspective view thereof, as installed on an exemplary fuel tank inlet conduit of a vehicle.

The broken lines in the drawings illustrate portions of the bib for a fuel tank inlet conduit and environmental structure of a vehicle that form no part of the claimed design.
